PHOTOCHROME, OF PARIS, FRANCE.

PHOTOGRAPHIC CAMERA.

No. 827,967.

Specification of Letters Patent.

Patented Aug. 7, 1906.

Application filed March 29, 1905. Serial No. 252,742.

To all whom it may concern:

Be it known that I, JEAN FRACHEBOURG, a citizen of the Republic of France, residing in and whose post-office address is No. 38 Boulevard Raspail, Paris, France, have invented new and useful Improvements in Photographic Cameras, of which the following is a specification.

This invention relates to a photographic camera for taking tricolor photographs or ordinary photographs, as required, the changing of the plates and the color-filter being effected simultaneously and mechanically by pressing a spring-knob or by pressing an air-ball.

In the accompanying drawings, Figure 1 is a longitudinal section approximately on the line 1 1 of Fig. 2. Fig. 1^a is a detail of the mechanism shown in Figs. 1 and 3. Fig. 2 is a front elevation. Fig. 3 is a vertical section approximately on the line 3 3 of Fig. 1. Fig. 4 is a front elevation of certain internal parts, the front wall of the filter-carrying disk and its mechanism being removed, the plane of section being indicated approximately by the line 4 4 in Fig. 1. Fig. 5 is an elevation of the filter-carrying disk and its releasing mechanism, the plane of section being along the line 5 5 in Fig. 7. Fig. 6 is an elevation approximately along the line 6 6 in Fig. 7, showing the mechanism for turning the filter-carrying disk and the shutter, the apparatus being set for tricolor photography. Fig. 7 is a vertical section approximately along the line 7 7 of Fig. 6. Fig. 8 is a detail of Fig. 6, showing the arrangement of the stop for the taking of ordinary one-color photographs. Fig. 9 is a detail of Fig. 5, illustrating the disk-releasing mechanism arranged for one-color photographs.

The apparatus comprises a disk A, fixed to a spindle a, the said disk being provided with three color-filters b b' b² and with a circular aperture c, which only serves for ordinary photography. This disk is also provided with pins d' d² d³ d⁴ d⁵ d⁶, which serve to momentarily stop the color-filters behind the objective B by coming in contact with a double detent or escapement e f. The upper tooth e is carried by a lever g, turning freely on a pivot h, and the free end of which abuts against a pin i under the action of a leaf-spring i', fastened to the top of the lever

and engaged under a fixed pin i², as shown in Fig. 5.

The lower tooth f forms part of a second lever j, which is pivoted at k upon the lever g and forms practically an adjustable part of this lever, the small arm of this lever being provided with a slot l, in which is engaged the stem of a screw m, which is eccentrically fixed upon the pivot h. This method of mounting the lever j allows, when the knob n on the front end of the pivot h is turned in the direction of the arrow, Figs. 2 and 6, of further separating the tooth f from the tooth e when requiring to take ordinary photographs, so that as long as the lever g and tooth e are held up the pins may pass freely. The knob n is also used for adjusting the spacing of the teeth. Fig. 5 shows the position of adjustment when the pivot h and screw m are horizontally in line; Fig. 9, the screw m in the highest position.

The lifting of the levers g and j is caused by pressing a spring-knob o, the stem of which terminates in a conical portion p, which by acting upon the short arm q of a lever r causes the said lever to swing upward about the pivot h. In this lifting movement a forwardly-projecting part s of the lever r lifts the levers g and j, and the escapement operates by one of the pins d', d², d³, d⁴, d⁵, and d⁶ passing the stop e and then as the levers are lowered passing the stop f. If desired, the lever r can be actuated by inflating an india-rubber bellows t by means of an air-bulb, the tube of which is fixed on the nozzle u. The lever r is also provided with a pin v, which keeps the metal plate w, forming the shutter, closed.

The filter-carrying disk A is actuated by a spring x, placed in a barrel y, which can be set up by turning a knob or handle z, mounted upon a spindle 1, on which is fixed a toothed sector 2, which gears with a pinion 3, fixed to the disk A by the screw a. The toothed sector 2 is provided with three pins 4, 5, and 6, the pins 4 and 5 being on the front and the pin 6 on the rear face of the sector. The pin 4 is designed to lift a pivoted bar 7, which closes the shutter w at the required moment. The second pin 5 acts against a stop or detent 8 to limit the action of the spring x. The third pin 6 is designed to transmit the movements of the toothed

sector 2 to the change mechanism of the plates, which must work simultaneously with the changing of the color-filter.

When the operation is commenced, by 5 pressing on the button *o* the levers *r*, *g*, and *j* are actuated. The pin *v*, carried by the lever *r*, is disengaged from the tooth *w'*, Fig. 6, at the upper edge of the shutter *w*. The shutter *w* is carried by an arm 36, fixedly 10 connected to an arm 37, pivoted at 38. The arm 37 carries a pin 39, on which acts the spring 32, tending to press the pin 39 downward. When the shutter is no longer retained by pin *v*, the spring 32 presses down 15 the pin 39 and shifts the shutter in the direction of the arrow in Fig. 6, opening the orifice. When the three plates have been exposed, the finger 4, carried by the toothed sector 2, lifts the lever 7, which acts on the 20 arm 37, which in the previous movement was brought against the end of the lever 7. Then the arm 37 is lifted, and the shutter is carried to its original position, and the pin *v* rides up on the inclined back edge of the tooth *w'* 25 on the shutter and over the tooth and again holds the shutter fixed.

The detent 8 is adapted to be adjusted to two different positions, in one of which, Fig. 6, the apparatus is adjusted for tricolor photography and in the other of which, Fig. 8, it is adapted for one-color photography. The adjustment of the detent 8 is effected by means of a cam 9, mounted on a pivot 10, which is turned by a knob 11 on the front of 30 the camera, having an index or pointer which in one position indicates "colors" and in the other position "black." The detent 8 is held against the cam 9 by means of a spring 12.

In taking tricolor photographs the filter-carrying disk makes three successive stops. 40 At the end of the third stop the pin 5, carried by the sector, comes against the stop 34 of the detent 8, which is in the position indicated in Fig. 6. The sector, and consequently the filter-carrying disk, cannot rotate farther, but must be turned backward to its starting position. When it is desired to take black photographs, the pin 5 is allowed to turn until it strikes the stop 34, as before. 45 Then the detent 8 is adjusted to the position of Fig. 8. In this position the pin 5 is caught by the stop 35 of the detent and can only swing backward and forward within the slot in the detent a sufficient space to allow the 50 hole *c* in the filter-carrying disk to pass to and from its position in line with the objective.

In order to allow of varying the rapidity of movement of the disk, the power of the spring *x* can be moderated as required by means of 60 a brake formed by a metal strip 13, held at one end by a screw 14, and the free end of which can be moved forward or back by turning a knob 15, the stem of which is a screw, which by screwing into the strip 13 causes 65 more or less pressure upon the point 16 of the

spindle 1, on which is fixed one of the ends of the spring *x*.

The connection between the change mechanism of the plates and that of the filter-carrying disk is established by the pin 6, which 70 turns a lever 17, mounted upon a spindle 18, carrying a cam 19, in the cam-slot of which is engaged a pin 20, which can slide in a vertical slot made in the partition 21 of the apparatus. A light spring 22 constantly acts upon the 75 spindle 18 to press the lever 17 against the pin 6. The pin 20 actuates a slide 23, which moves vertically and carries a double cross-arm 24, having at its ends pins or trunnions 25, Fig. 1^a, engaged in slots made in the ends 80 of two rocking bars 26, the rear ends of the 85 bars being drawn toward their lowermost position by means of springs 27. The lower arms of the said bars are each provided with four ratchet-teeth 28, (as many as there are holes 85 in the disk A,) designed to effect the changing of the plates. To this end the plates are placed in metal frames, having on their lower edges projecting pins 29, located between a lower angle-bar 30 and an upper plate 31. 90 These pins 29 are seized by the teeth 28 of the bars 26 when the filter-carrying disk A turns one division, and a photographic plate has at the same time to be changed.

The projecting pin 29, which is at the edge 95 of the plate-carrying frame, rests on an angle-piece 30 and runs under the lower edge of the plate-guide 31. A spring 31^a, arranged behind the frames, tends to push them always forward. The racks 29 at the beginning 100 stand in the position shown in dotted lines in Fig. 1. When the rack 26 presents one of its notches to the pin 29, this pin is pushed by the spring 31^a under the tooth of the rack. As the rack 26 falls its tooth bears on the pin 105 29, pulling down the pin and the frame until the pin comes opposite the opening above the inclined plane 33, whereupon the pin slides off the beveled upper edge of the tooth and onto the inclined plane, which guides the pin 110 and frame to their proper position in the bottom of the apparatus. It is to be observed that the angle-bar 30 extends horizontally a less distance than the length of the pin 29, so that when the latter escapes over the end of 115 the bar 29, the plate-holder may fall freely.

When requiring to take tricolor photographs, the apparatus is set by turning the knob *z*, which places the parts in the position shown in Figs. 5 and 6, the knobs *n* and 11 120 *o* being in the position indicated in Fig. 6 and the bars 26 being turned upward. When the knob *o* is pressed, the lever *r* is raised and carries with it the two other levers *g* and *j*. The first movement which is produced is the 125 rotation of the shutter *w*, which exposes the objective under the action of a spring 32, the said shutter being no longer retained by the pin *v*. The second movement, caused by releasing pressure on the knob *o*, is the passing 130

of the color-filter *b* behind the objective, the first pin *d*⁶ having passed between the teeth *e f*, while the lowermost ratchet-teeth 28 of the bars change the first plate by causing the pins 29 to slide over the inclined planes 33 in order to lay this plate in the bottom of the apparatus. To expose the second plate behind the second color-filter *b'*, the knob *o* is pressed a second time and released, and the said second plate is changed by the second ratchet-teeth of the bars 26. The knob *o* is pressed a third time and released in order to expose and change the third plate. As soon as one first plate has been exposed one of the color-screens of the disk A being in position opposite the objective, this disk advances under the action of a second movement of the button, and it is while it moves behind the objective over the angular interval which separates two successive color-screens that the first plate falls, so that during the falling the first plate can receive no further impression and the second plate cannot have already received one. This second plate receives no impression until the disk A has terminated the angular movement above referred to and the second color-screen has been placed behind the objective. The second plate then receives its impression. The same movement occurs for the third plate. When the third plate has been exposed, the pin 4 on the toothed sector 2 engages the incline 50 and lifts the pivoted bar 7, the nose of which causes the shutter *w* to again close. At the end of the movement the pin 5 comes in contact with the stop 34 on the detent 8, and the apparatus must be set afresh if it is desired to continue with tricolor photography. When it is required to take ordinary photographs, the knobs *n* and 11 are half-turned, which causes the detent 8 and the lever *j* to assume the position represented in Fig. 8 and 9. The apparatus is then set by turning the handle *z*, which causes the disk A to take the position shown in Fig. 9, the pin 5 lying in the slot of the detent 8. When the knob *o* is pressed, the disengagement is effected, the shutter *w* opens, and the hole *c* passes in front of the objective to expose the plate, which falls into the bottom of the apparatus. At the same time that the plate is changed the pin 4 engages the incline 51 and lifts the pivoted bar 7, which closes the shutter again.

I claim as my invention—

1. In a photographic camera, in combina-

tion, change mechanism for color-filters, change mechanism for plates, and a connecting means between said mechanisms adapted to cause the simultaneous change movement of the color-filter with that of the exposed plate, substantially as set forth. 60

2. In a photographic camera, the combination of color-filters and plates, a spiral spring *x* which is set up from the outside, a toothed sector 2 actuated thereby, three pins 65 4, 5, 6, carried by said sector, a shutter actuated by the pin 4, a detent for said spring adapted to be engaged by the pin 5 and to permit a limited play thereof, and change mechanism for the plates actuated by the pin 70 6, substantially as set forth.

3. In a photographic camera, in combination, a spiral spring *x*, two pivoted bars 26 adapted to be swung by said spring, plate-carriers provided with pins 29, and ratchet-teeth 28 on said bars 26 adapted to engage said pins to shift a carrier from its exposed position, substantially as set forth. 75

4. In a photographic camera for taking tricolor photographs, or ordinary photographs, 80 as required, the combination of a spiral spring *x*, a cam 9, and a detent 8 the position of which can be varied by means of said cam 9 for limiting the play or the expansion of the spiral spring *x* according to whether it is required to take tricolor photographs or ordinary photographs, substantially as set forth. 85

5. In a photographic camera for taking tricolor photographs, or ordinary photographs, as required, the combination of color-filters 90 *b*, *b'*, *b*², a disk A carrying said filters, a double detent or escapement for controlling the rotation of said disk, the said escapement consisting of two teeth *e f*, superposed levers *g j*, carrying said teeth *e* and *f* respectively, 95 one of the said levers *j* being adapted to be moved over the other in order to separate the teeth *e f*, from one another when requiring to take ordinary photographs, said disk having a hole *c* not provided with a color-filter, 100 said parts being arranged to allow the hole *c* to pass behind the objective followed by the shutter, substantially as set forth.

In witness whereof I have hereunto signed my name, this 14th day of March, 1905, in 105 the presence of two subscribing witnesses.

JEAN FRACHEBOURG.
